UNITED STATES PATENT OFFICE.

WILLIS E. MANN, OF NAPA, CALIFORNIA.

APPARATUS FOR CLEANING SACKS.

No. 869,585.

Specification of Letters Patent.

Patented Oct. 29, 1907.

Application filed May 23, 1906. Serial No. 318,405.

To all whom it may concern:

Be it known that I, WILLIS E. MANN, a citizen of the United States, residing at Napa, in the county of Napa and State of California, have invented certain new and 5 useful Improvements in Apparatus for Cleaning Sacks, of which the following is a specification.

My invention relates to improvements in means or apparatus for cleaning sacks, more particularly cement-sacks.

10 Its object is to provide for accomplishing that purpose both by mechanical means and the action of compressed air delivered into the sacks; and to promote simplicity and economy in the manner of carrying out the same, as well as to perform the cleaning action in 15 the minimum time and with effectiveness.

Said invention consists of certain features substantially as hereinafter fully disclosed and specifically pointed out by the claims.

In the accompanying drawings illustrating the preferred embodiment of my invention—Figure 1 is a view showing principally a gang or number of sack holders and beaters in edge elevation, characteristic of said invention, a sack appearing in dotted lines in position upon one of the beaters for cleaning. Fig. 2 is a view 25 also in elevation taken at right-angles to the view-point of Fig. 1, a sack in like manner being also represented upon the only beater disclosed by this view. Fig. 3 is an enlarged detailed view taken at right-angles to the view-point of Fig. 2, showing a broken detached enlarged view of one of the holders or frames and beaters proper carried thereby. Fig. 4 is 30 an enlarged detailed view showing more especially one of the beater spring thrusting connections or joints. Fig. 5 is a vertical section of one of the beaters. Fig. 6 is an enlarged detailed sectional view showing more clearly the collar at the point of conjunction between 35 the air-receiving pipe and its carrying shaft, together with the air-inlet nozzle for connection with a hose leading from a compressed-air source of supply.

In the disclosure of my invention, I suitably mount in position upon suitable timbers or supports 1, transverse rock-shafts 2 having their tubular bearings 3, secured to said timbers, and said shafts are suitably equipped with arms 4, preferably sleeved and keyed thereon as at 5, 6 to stand vertically, and are themselves provided near their extreme upper ends with lateral 45 pins or studs 7, the action of which will presently be seen.

Suitably carried and actuated by the rock-shafts 2, are upright frames or holders 8 for carrying or holding the sacks to be cleaned, an example of which being 50 disclosed by dotted lines in Figs. 1 and 2. Each frame or holder comprises preferably vertical lateral rods or bars 9 whose lower ends are suitably secured to their respective rock-shafts 2 and their upper ends connected to, and bearing a hollow or tubular member 10, 55 which, for convenience, is composed of a number of tube or pipe sections and centrally depending from,

and communicating with which is a pipe 11, opening into, and having screwed thereon at its lower end a coupling or collar 12 keyed or otherwise held upon said shaft passing transversely therethrough. The 60 horizontal or connecting tubular member 10 between the lateral bars or members of each sack-carrying frame or holder is provided with numerous apertures *a*, *a* for the delivery of the compressed air or blast into the sack for utilizing the same in aiding the elimination of 65 particles adhering to the sack and the dust thus created therefrom. The collar or coupling 12 has produced therein a laterally opening diagonal passage 13 also opening into the lower end of the pipe 11 and into said passage is screwed a nozzle 14 to which, in practice, is to be applied one end of a hose or pipe (not shown) leading to a suitable supply or source of compressed air for delivery into the pipe 11 and finally into the sack for aiding the cleaning thereof as will be readily appreciated. Said sack holders or frames are 70 each provided or equipped with preferably duplicate beaters 15 arranged upon opposite sides of the pipe 11, for mechanically aiding the cleaning operation or agitating the sacks. Each beater or agitator comprises two stud-bolts 16 the lower one passing transversely 75 through a shaft 2 and the upper one passing transversely through the pipe or tube member 10, and intermediate pieces 17 secured or clamped transversely to, and upon opposite edges of eye-bars 18. Said eye-bars are connected to links 19, 20, the link 19, in turn being 80 connected to the upper stud-bolts 16 and the link 20 passing through the upper end bar of a preferably rectangular or frame member 21 of what may be termed an endwise-thrusting connection or joint 22 articulated or pivotally connected to the lower stud-bolts 16. 90 The other member of said joint or connection 22, in the form of a preferably coiled spring 24, is arranged upon the nut-equipped lower end-portion of the link 20, within said rectangular or frame member 21, said spring exerting its stress or tension upon the nut and 95 said frame-member. This arrangement provides as is apparent, for additional flexing movement of the beaters, accordingly for a greater or extended length of stroke, whereby a more effective beating action is obtained, especially as is required in certain kinds of 100 work. Said intermediate pieces 17 have secured thereto and carry at their ends longitudinal bars 25 adapted to engage or operate upon the sack throughout its length as the sack-carrying frame or holder is actuated by the swinging or oscillating motion thus 105 imparted to said bars, out of the plane of the sack-carrying frame or holder for the effective cleaning of the sack or detaching adhering material therefrom which, as already stated, will be aided by the current of compressed air delivered into said sack or sacks. A suitably driven second shaft 26 is supported or journaled 110 in position, in a plane above that of the shaft 2 and at

right-angles thereto, upon preferably right-angled bracket-castings 27 having their lower portions each forming an additional right-angle to conform to and rest upon the upper surface of one of the timbers 1, to 5 which it is suitably bolted. Said shaft 26 is provided with a number of grooved cams 28 whose grooves receive the pins 7 of the shaft-arms 4 and accordingly provide, as said shaft is driven, for rocking or oscillating the shaft 2, thus imparting a corresponding motion to 10 the sack-carrying frames and the beaters for delivering a beating action upon the sacks supported in position as aforesaid.

A dust-receiving pan or chute 29 is suitably arranged and held in position immediately under the sacks, the 15 open ends of the latter depending contiguous to the upper edge of said pan to permit the ready reception thereinto of the dust and other adhering particles detached from said sacks.

A suction-pipe 30 is suitably arranged directly below and in line with the vertical longitudinal center of the dust-receiving pan or chute 29, the latter being adapted to deliver its contents through a longitudinal central opening in its bottom into said suction-pipe as is apparent particularly from Fig. 2. Said pipe has 25 arranged at its delivery end an exhaust fan (not shown) for creating a suction therein for the thus suitable withdrawal of the dust &c., from said pipe as will be readily understood.

I claim—

30 1. A machine of the character described, comprising a frame or holder adapted to permit the inversion of a sack thereover, an agitator or beater carried by said holder for operating upon the sack, a grooved-cam equipped shaft for engaging and actuating said holder and agitator, and 35 means for operating said shaft.

40 2. A machine of the character described, comprising an oscillating frame or holder adapted to permit the inversion of a sack thereover, an agitator or beater carried by said holder for operating upon said sack, and means for actuating said holder and beater or agitator, said frame or holder embracing hollow or tubular members having apertures for delivering compressed air into said sack for aiding the removal of adhering particles and dust therefrom.

3. A machine of the character described, comprising a rock shaft carrying an upright frame or holder adapted to 45 permit the inversion thereover of a sack, an agitator or beater connected to said frame and actuated by said rock-shaft and adapted to operate upon said sack and a cam-equipped shaft for actuating said rock-shaft said frame or holder embracing tubular or hollow members equipped 50 with apertures for delivering compressed air into said sack.

4. A machine of the character described, comprising a number of oscillating frames or holders each adapted to 55 permit of the inversion of a sack thereover, a number of beaters arranged in connection with said frames or holders, means for actuating said frames or holders and said beaters, said beaters each comprising longitudinal agitating bars, parallel cross-bars connecting said longitudinal bars, links connected to eye-bars interposed between said parallel cross-bars, rock-shafts and means effecting connection between said links and said frames or holders and said rock-shafts.

5. A machine of the character described, comprising an oscillating frame or holder adapted to permit the inversion 60 of a sack thereover, a beater arranged in connection with said frame or holder, and a rock-shaft effective for actuating said frame or holder and said beater, said beater comprising longitudinal agitating bars, parallel cross-bars connecting said longitudinal bars, links connected to eye-bars interposed between said parallel cross-bars, stud-bolts connected to the top-end of said oscillating frame or holder and to said rock-shaft, respectively, one of said links being connected to one of said stud-bolts, a coupling or joint member between the other of said stud-bolts and the other of said links, and a spring exerting its stress or 65 pressure upon said coupling or joint member and said latter link.

6. A machine of the character described, comprising a rock-shaft, means for operating the same, an oscillating frame or holder carried by said rock-shaft and having an 70 apertured tubular member, said frame being adapted to permit the inversion of a sack thereover, and means for operating upon said sack connected to said frame, said frame or holder having a pipe, connecting with said tubular member and coupled to said shaft and provided with 75 a nozzle adapted to have connected thereto a hose or pipe leading to a source of supply of compressed air.

In testimony whereof I have signed my name to this specification in the presence of two subscribing witnesses.

WILLIS E. MANN.
